UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

STRIP-CONTROLLING DEVICE FOR SEWING-MACHINES.

1,289,127.

Specification of Letters Patent. Patented Dec. 31, 1918.

Application filed May 16, 1917. Serial No. 168,949.

To all whom it may concern:

Be it known that I, ALBERT H. DE VOE, a citizen of the United States, residing at Westfield, in the county of Union and State of New Jersey, have invented certain new and useful Improvements in Strip-Controlling Devices for Sewing-Machines, of which the following is a specification, reference being had therein to the accompanying drawings.

This invention has to do with sewing machines in general and with guiding devices therefor in particular.

In the manufacture of overalls it is desirable to reinforce the junction of the bib and the body or nether portions thereof with a strip or tape applied to the under side of the goods to conceal it from view. The strip extends transversely of the garment and its ends are finished off neatly by doubling them under transverse the length of the strip. The raw edges of unselvaged strips are liable to ravel and it is preferable to hem or fold them under. Heretofore it has been common to stitch the hemmed edges of such strips to the garment entirely across the width of the bib, to cut the tape and then to rip out the stitches adjacent the edges of the bib in order to fold 30 the ends under and finish them off neatly.

It is the purpose of this invention to avoid the time consuming operation of ripping out stitches at the ends of the strip or tape by diverting the edges of the strip from under the needles as they pass the stitching point.

The invention is characterized by a marked simplicity of construction and efficiency in operation which will appear in the following description of the preferred of many possible embodiments thereof illustrated in the accompanying drawings, in which Figure 1 is a perspective view of the device assembled on a machine, parts being broken away to more fully expose the invention. Fig. 2 is a perspective view of the strip-guiding device in coöperative relation with the edge-guiding device. Fig. 3 is a perspective of the bottom side of the attachment, the strip-guiding device being shown as it would appear sectioned on line A—B Fig. 1. Figs. 4 and 5 are cross sections of a garment at the junction of the

bib and body sections showing the different conditions in which the reinforcing strip passes the needles. Fig. 6 is a perspective of the preferred form of channeled throat-plate. Fig. 7 is a plan view of a modified form of throat-plate. Fig. 8 is a detail showing the two positions of the delivery end of the strip-guiding device. Figs. 9-11, inclusive, illustrate a modification of the invention and Figs. 12-14, inclusive, show a further modification of the invention.

Coöperating with any suitable form of under-thread handling mechanism are a pair of spaced needles 1 entering needle-holes 2 in a throat-plate 3 which is cut away in advance of the needle-holes as indicated clearly in Fig. 6 of the drawings. The opening so formed is defined by vertically extending walls, 4, 5 and 6. The walls 5 and 6 are oppositely convergent relative to the direction of feed and are located immediately in advance of the needles. The wall 4 is parallel with the needles and is not as high as the convergent walls, the throat-plate being milled out in rear thereof, as indicated on the drawing by the surface 7, to furnish clearance. The inclined walls 5 and 6 extend past the wall 4 a short distance where they join parallel and vertically extending walls 9 and 10 spaced apart a less distance than the needles between which they are disposed. These walls 9 and 10 diminish in height in the direction of feed until they disappear slightly in rear of the needles. Collectively the walls 5-9 and 6-10 form an edge-guiding or edge-diverting device for contracting a strip, delivered thereto from a strip-guide and normally wider than the needles are apart, from the range of action of the stitch-forming mechanism and for leading the strip past the needles with its edges between and to one side of the same. Laterally of the walls 5 and 6 the upper surface of the throat-plate is chamfered as indicated at 5' and 6' to facilitate the contracting of the strip as will appear more clearly as the description proceeds.

A strip-guiding device 11 is also located in advance of the needles with its flat tubular delivery end 12 beveled off at the corners as indicated at 13 in conformity with

the convergent walls 5 and 6, the walls and corners being disposed substantially in parallelism—see Fig. 2. The strip-guide 11 is provided with edge-folding portions 14 and a spring-tongue 15 which terminate short of the end edges 16 of the tubular delivery portion 12. The end edges 16 overlap, when lowered as shown in dotted lines, Fig. 8, the inclined surface 7.

10 The strip-guiding device 11 is formed with a depending lip or plate 17 having an open-ended slot 18 and parallel sides 17' for enabling the guide to be adjustably secured by means of a clamping screw 19 and steady pins 19' to the wing or extension 20 of a sleeve 21 secured on one end of a rock-shaft 22. The shaft 22 is suitably journaled in spaced bearing lugs 23, Fig. 3, depending from a supporting plate 24 removably secured to the cloth-plate 25 by screws 26, endwise movement of the shaft 22 being prevented by a sleeve 27 and a collar 27' clamped by a screw 28 to the shaft on opposite sides of one of the bearing lugs 23.

25 An arm 29 suitably fixed to the other end of the rock-shaft 22 carries a friction-roller 30 adapted to enter the slotted cam-end 31 of a knee-shift lever 32 pivoted at 33 to a bracket-arm 34 secured by screws 35 to the supporting plate 24. A spring 36, fixed to the lever adjacent the pivot 33, is so constructed and arranged with relation to a block 37, suitably secured to the plate 24, that it normally holds the lever 32 in the position shown in Fig. 1 of the drawings with the roller 30 near the open end of the cam slot and the strip-guiding device raised. The inner closed end of the cam-slot is farther from the pivotal axis 33 than the open end so that when the lower end of the lever 32 is swung to the right, from the position shown in Fig. 1 to that shown in Figs. 2 and 3, the arm 29 is swung upwardly and the strip-guiding device 11 downwardly, 40 thereby depressing the delivery end of the strip-guiding device from a position above the upper surface of the throat-plate to a position below the same and between the convergent walls 5 and 6 as indicated in 45 dotted lines in Fig. 8.

50 Located in advance of the needles is a hemmer 40 hinged at 41 to a removable section 42 of the cloth-plate 25 on which section is also suitably mounted an edge gage 43. The hemmer is adapted to fold under the lower edge of the bib-sections and the edge gage to properly locate the upper edge of the lower or nether portions of the garment relative to both the bib sections and the reinforcing strip. With the horizontally hinged hemmer cross seams or other inequalities in the garment may be accommodated. The strip-guiding device 11 is inclined upwardly from beneath the cloth-plate 25 and its delivery end 12 pro-

jected through an aperture 44 in the section 42 of said cloth-plate.

55 In the normal operation of the machine the delivery end edges 16 of the strip-guide occupy a position above the upper surface 70 of the throat-plate and direct the strip over the chamfered positions 5' and 6' to and under the needles. This position of the strip-guiding device is indicated in Fig. 1 and in Fig. 8, in solid lines. The edge-guiding or diverting device, comprising the walls 5—9 and 6—10, is wholly idle and therefore ineffective during the normal operation of the machine when the strip-guiding device is in the position above mentioned. When the side edge of a garment is approached during a stitching operation the operator has only to press the knee-shift lever 32 to the right in order to depress the delivery end of the strip-guiding device 85 down in between the convergent walls 5 and 6, in which coöperative relation of the devices the edges of a strip will be deflected inwardly and the strip contracted in width as it passes the needles. This diverting 90 action is clearly portrayed in Figs. 2, 4 and 5 of the drawings. During the normal operation of the machine when the strip-guiding device 11 is in the position shown in Fig. 1, the lower of the end edges 16 of the flat tubular delivery end 12 smooths or irons out flat the intermediate portions of the strip.

95 In the manufacture of corsets it is often desirable to leave an entrance or opening 100 at one side of the bone casing or strips covering the steels for facilitating the insertion of stiffeners. In such cases it would be desirable to withdraw only one edge of a strip from the action of the needles. This could be done readily either by dispensing entirely with one of the vertical edge-diverting walls or arranging one parallel with the line of feed at or beyond the line in which its corresponding edge of the strip travels. Such 105 a modification is indicated at 50 in Fig. 7 of the drawings. In this case, of course, the corresponding corner of the strip-guiding device may or may not be beveled, as desired.

110 It will be observed that the present strip-guiding device, in the normal operation of the machine when both edges of a strip are being penetrated by the needles, directs the strip to the stitching point without any assistance from the edge-diverting walls 5—6 on the throat-plate, inasmuch as the edges of the strip necessarily pass over the chamfered portions 5' and 6' in order to pass under the needles. Normally the strip-guiding device is the sole means for directing the strip to the needles and normally therefore the edge-diverting or edge-guiding device is ineffective. When the strip-guiding device is depressed into coöperative relation with 120 125 130

the edge-diverting device it directs the strip in between the convergent walls 5 and 6 and renders both devices simultaneously effective, the former leading the strip to the latter which acts to turn the edges of the strip to one side so that they may pass between the needles, the intermediate portions of the strip being crimped longitudinally. It is to be noted also, that the strip-guiding device 10 is moved into coöperative relation with the edge-guide or edge-diverting device during the operation of the machine.

In the foregoing the principle of operation consists in drawing the edges of a strip 15 down across the convergent walls during the operation of the machine when through co-operation of the walls and feed-dogs the edges of a strip will be diverted from their normal paths under the needles, the action 20 being dependent upon the movement of the strip-guiding device relative to the edge-diverting device.

Substantially the same principle of operation is relied upon to effect withdrawal of the 25 edges of a strip in the modifications of the device shown on Sheet 3 of the drawings.

In the modification shown in Figs. 9-11, inclusive, a strip-guiding device 111 is provided with a plurality of crimping fingers 30 112 extending from the upper wall of its flat delivery or discharge end 113. Crimping channels 114 are formed in the throat-plate 115 in advance of the usual feed-dog slots and are shaped to mate with the fingers 112.

35 The strip-guiding device 111 may be supported and moved by any suitable mechanism, such as that shown and described in connection with the preferred form of invention illustrated in Figs. 1-6, inclusive. 40 When the strip-guiding device is depressed from the solid line position shown in Fig. 11 to carry the fingers 112 into the crimping channels 114, the edges of the strip passing through the folder are withdrawn from the 45 action of the needles.

In the modification shown in Figs. 12-14, inclusive, a single crimping finger 212 is slidably secured by clips 213 and screws 214 to a fixed or relatively fixed portion 215 of 50 the cloth-plate so as to be movable relative to a strip-guiding device 216 upwardly inclined beneath a cloth-plate and supported in any suitable manner. Through the strip-guiding device a strip may be led over the 55 rounded edge 230 of the throat-plate 231 to the spaced needles of the stitch-forming mechanism. The parallel walls of the delivery portion of the strip-guiding device 216 are cut away, as indicated by the slots 217 and 218, to allow the finger 212 being held retracted, as shown in solid lines Fig. 60 13, by the spring 219 secured at one end to a pin 220 fixed to the finger 212 and at its 65 other end to a pin 221 fixed to one of the clips

213. The finger may be advanced manually by any suitable agency directed endwise against it, as indicated by the arrow at 222. When the finger 212 is advanced through the strip-guide 216 it will crimp or buckle the 70 material intermediate its edges and out through the open-ended slot 218 thereby withdrawing the edges of the strip from the action of the needles.

In the modifications found in Sheet 3 of 75 the drawings, it will therefore be apparent that a relative bodily movement between a strip-guide and a normally ineffective crimping device is relied upon to effect a withdrawal of the edges of a strip from the 80 action of spaced needles just as a relative bodily movement between a strip-guide and a normally ineffective element is relied upon to produce the same result in the preferred form of the invention shown in Figs. 1-6 of 85 the drawing.

Having thus set forth the nature of the invention, what I claim herein is:—

1. In a sewing machine, in combination, 90 stitch-forming mechanism including spaced needles, feeding mechanism, a normally ineffective edge-diverting device, an independent and continually effective strip-guiding device, said devices being relatively movable during the operation of the machine for rendering both simultaneously effective whereby at least one edge of a strip being stitched may be withdrawn from the action of the needles without stopping the stitch-forming mechanism.

100 2. In a sewing machine, in combination, stitch-forming mechanism including a needle and work-feeding mechanism, a guide, an edge-diverting wall located between the guide and the needle, and means for moving said guide and wall relatively into coöperative relation whereby one edge of material passing through the guide may be led under or to one side of the needle.

110 3. In a sewing machine, in combination, 115 stitch-forming mechanism including a needle, feeding mechanism, a strip-guide, and additional means having an active diverting wall located in advance of the needle for contracting the width of a strip as it passes the needle, said strip-guide being movable into and out of coöperative relation with said additional means during the operation of the machine.

120 4. In a sewing machine, in combination, 125 stitch-forming mechanism including spaced needles, feeding mechanism, a strip-guide, and means independent of said strip-guide for crimping the strip between its edges whereby as it is fed past the needles one or more of said edges may be withdrawn from the action of the stitch-forming mechanism.

130 5. In a sewing machine, in combination, stitch-forming mechanism including spaced needles, work-feeding mechanism, a strip-

guide continuously effective in directing the strip toward the stitch-forming mechanism parallel to the direction of feed, and an edge-guide having a surface for diverting the 5 edge of the strip laterally of the line of seam formation, said strip and edge-guides being relatively movable into and out of coöperative relation.

6. In a sewing machine, in combination, 10 stitch-forming mechanism including spaced needles, feeding mechanism, an edge-diverting device located in advance of the needle, a strip-guiding device located in advance of the edge-diverting device, said edge-diverting 15 device being normally located at one side of the path of a strip from the strip-guiding device to the feeding mechanism, said devices being relatively movable to position the edge-diverting device in or across the path 20 of the strip from the strip-guiding device to the feeding mechanism and to render it effective without stopping the machine.

7. In a sewing machine, in combination, 25 stitch-forming mechanism including spaced needles, work-feeding mechanism, edge-diverting walls fixed relatively to the needles and in advance thereof, a strip-guiding device movable during the operation of the machine about an axis located in advance of 30 and extending transverse to the paths of movement of the needles.

8. In a sewing machine, in combination, 35 stitch-forming mechanism including spaced needles, feeding mechanism, an edge-guiding device, a strip-guiding device, said devices being relatively movable, said edge-guiding device including walls converging toward each other in the direction of feed and at least one of which is disposed across 40 the line of seam formation in advance of a needle, whereby when the devices are moved relatively at least one edge of a strip may be deflected from its corresponding needle.

9. In a sewing machine, in combination, 45 stitch-forming mechanism including spaced needles, feeding mechanism, an edge-guiding device, a strip-guiding device, said edge-guiding device including walls oppositely convergent relative to the direction of feed 50 and in advance of the needles, and means for moving said devices relatively.

10. In a sewing machine, in combination, 55 stitch-forming mechanism including spaced needles, feeding mechanism, an edge-guiding device, a strip-guiding device, said edge-guiding device including walls equally and oppositely convergent relative to the direction of feed, means for moving said devices relatively into coöperative relation including 60 a slotted cam-lever, an arm operated thereby, and operative connections between said arm and one of said devices.

11. In a sewing machine, in combination, 65 stitch-forming mechanism including spaced needles, feeding mechanism, a continually

operative strip-guiding device, an edge-diverting device normally ineffective upon the strip, said devices being relatively movable during the operation of the machine for rendering both simultaneously effective upon 70 the strip whereby at least one edge of a strip being stitched may be withdrawn from the action of the needles without stopping the stitch-forming mechanism, and means for moving said devices relatively into coöperative relation. 75

12. In a sewing machine, in combination, 80 stitch-forming mechanism including spaced needles, feeding mechanism, a continually effective strip-guiding device, an edge-diverting device normally ineffective upon the strip, said devices being relatively movable during the operation of the machine for rendering both simultaneously effective upon 85 the strip whereby at least one edge of a strip being stitched may be withdrawn from the action of the needles without stopping the stitch-forming mechanism, and means for moving said devices relatively a predetermined distance into coöperative relation. 90

13. In a sewing machine, in combination, 95 stitch-forming mechanism including spaced needles, feeding mechanism, a continually effective strip-guiding device, an edge-diverting device normally ineffective upon the strip, said devices being relatively movable during the operation of the machine for rendering both simultaneously effective upon 100 the strip whereby at least one edge of a strip being stitched may be withdrawn from the action of the needles without stopping the stitch-forming mechanism, and means for moving said devices relatively into coöperative relation including a spring for holding 105 said strip-guiding device in normal operative position.

14. In a sewing machine, in combination, 110 stitch-forming mechanism including spaced needles, feeding mechanism, an edge-guiding device, a strip-guiding device, said edge-guiding device including fixed walls having relatively convergent faces in advance of the needles and relatively parallel faces laterally of the needles, said strip-guiding device having the corners of its delivery end beveled 115 off to fit within the space between said convergent faces of the walls, said devices being relatively movable during the operation of the machine.

15. In a sewing machine, in combination, 120 stitch-forming mechanism including spaced needles, feeding mechanism, an edge-guiding device, a strip-guiding device, said edge-guiding device including relatively fixed walls having relatively convergent faces in 125 advance of the needles and relatively parallel faces laterally of the needles, said strip-guiding device having the edges of its delivery end beveled off to fit within the space between said convergent faces of the walls, 130

said devices being relatively movable, and means for moving the delivery end of said strip-guiding device into and out of said space between the walls for coöperation 5 therewith.

16. In a sewing machine, in combination, stitch-forming mechanism including spaced needles, feeding mechanism, an edge-guiding device, a strip-guiding device, said edge-guiding device including fixed walls having relatively convergent faces in advance of the needles and relatively parallel faces laterally of the needles, said strip-guiding device having the edges of its delivery end 10 beveled off to fit within the space between said convergent faces of the walls, said devices being relatively movable during the operation of the machine, and manual means for moving said devices relatively into coöperative relation and automatic means for moving said devices relatively out of coöperative relation.

17. In a sewing machine, in combination, stitch-forming mechanism including a pair 25 of spaced needles, feeding mechanism, a strip-guiding device, a throat-plate having edge-guiding walls fixed thereto in advance of the needles and convergent in the direction of feed, a pivotal support for said strip-guiding device, said pivotal support extending perpendicularly to a vertical plane through the line of feed, and means for swinging the delivery end of said strip-guiding device about the axis of said pivotal 30 support whereby the edges of a strip may be led under or to one side of the needles.

18. In a sewing machine, in combination, stitch-forming mechanism including a pair 40 of spaced needles, feeding mechanism, a throat-plate a normally ineffective edge-diverting device fixed relative to said throat-plate, a folder, a pivotal support for said folder, means connected with said pivotal support for swinging the folder about the 45 axis of its pivot into and out of coöperative relation with said edge-diverting device, whereby the normally ineffective edge-diverting device may be rendered effective to lead the edges of a strip to one side past the 50 needles during the operation of the machine.

19. In a sewing machine, in combination, stitch-forming mechanism including a pair 55 of spaced needles, feeding mechanism, a throat-plate, a normally inoperative edge-guiding device fixed relative to said throat-plate in advance of the needles, said edge-guiding device comprising convergent walls spaced farther apart at their receiving ends than at their delivery ends and disposed in 60 advance of the needles, a strip-guiding device having edge-folding portions, a shaft fixedly connected with said strip-guiding device and supporting the same, manual means for rocking said shaft and strip-guiding device, and means for normally holding 65

said strip-guiding device spaced from and out of coöperative relation with said edge-guiding device.

20. In a sewing machine, in combination, stitch-forming mechanism including spaced 70 needles, work-feeding mechanism, a strip-guiding device, an edge-diverting device, said devices being relatively movable during the operation of the machine and said strip-guiding device being normally positioned to direct the edges of a strip under the needles without subjecting them to the action of the edge-diverting device, and means for moving said strip-guiding device to a position subjecting the edges of the 80 strip to the action of the edge-diverting device.

21. In a sewing machine, in combination, stitch-forming mechanism including spaced 85 needles, feeding mechanism, a strip-guiding device having a discharge orifice wider than said needles are spaced apart for directing the edges of a strip under the needles, and a device for crimping a strip pulled by the feed through said strip-guiding device, said 90 devices being relatively movable during the operation of the machine to withdraw the edges of a strip from the normal path under the needles to an abnormal path between the needles.

22. In a sewing machine, stitch-forming mechanism including spaced needles, feeding mechanism, a strip-guiding device having a discharge orifice of fixed width exceeding the lateral distance between the 100 needles transverse the direction of feed, said strip-guiding device being adapted to direct the edges of a strip under the needles, in combination with a crimping device, said devices being relatively movable during the 105 operation of the machine without stopping the stitch-forming mechanism whereby the edges of a strip may be withdrawn from the action of the needles at will.

23. In a sewing machine, in combination, 110 stitch-forming mechanism including spaced needles, feeding mechanism, a strip-guiding device having a delivery end fixed against movement laterally of the line of feed and laterally of said spaced needles, means for 115 crimping a strip passing through said strip-guiding device, said means and said strip-guiding device being relatively movable during the operation of the machine whereby the edges of a strip led by said strip-guiding device to said spaced needles may be withdrawn from their action without stopping the stitch-forming mechanism.

24. In the combination set forth in claim 23, the strip-guiding device inclined upwardly from beneath and with its delivery end normally at substantially the same elevation as the horizontal plane of the feed.

25. In the combination set forth in claim 23, a hemmer and an edge-gage located 130

above the horizontal plane of feed, the strip-guiding device being inclined upwardly from beneath the horizontal plane of feed.

26. In the combination set forth in claim 5 23, a hemmer movable toward and from and located above the horizontal plane of feed, and an edge-gage.

27. In the combination set forth in claim 10 23, a cloth-plate having a movable section, a hemmer and an edge-gage mounted on said section in fabric directing relation with the spaced needles, said hemmer and edge-gage being movable with said section.

28. In a sewing machine, in combination,

stitch-forming mechanism including spaced 15 needles, work-feeding mechanism, a strip-guiding device, an edge-diverting device, said strip-guiding device normally directing both edges of a strip under the needles without subjecting the edges of the strip to the 20 action of the edge-diverting device, and means for relatively moving said devices to subject the edges of the strip to the action of the edge-diverting device.

In testimony whereof, I have signed my 25 name to this specification.

ALBERT H. DE VOE.
